UNITED STATES PATENT OFFICE.

DONALD F. LYBARGER, OF CLEVELAND, OHIO.

DESIGN FOR A BADGE.

Application filed March 31, 1926. Serial No. 17,142. Term of patent 3½ years.

To all whom it may concern:

Be it known that I, DONALD F. LYBARGER, a citizen of the United States, residing at Cleveland, in the county of Cuyahoga and State of Ohio, have invented a new, original, and ornamental Design for a Badge, of which the following is a specification, reference being had to the accompanying drawing, forming part hereof, wherein—

Fig. 1 shows an elevation of my new badge, and Fig. 2 a top edge view of such new badge.

I claim:

The ornamental design for a badge, as shown.

DONALD F. LYBARGER.
